UNITED STATES PATENT OFFICE.

GEORGE A. JOHNSON, OF CHICAGO, ILLINOIS, ASSIGNOR TO WILLIAM H. MINER, OF CHICAGO, ILLINOIS.

DRAFT-RIGGING FOR RAILWAY-CARS.

1,070,037.

Specification of Letters Patent. Patented Aug. 12, 1913.

Application filed July 22, 1912. Serial No. 710,752.

To all whom it may concern:

Be it known that I, GEORGE A. JOHNSON, a citizen of the United States, residing at Chicago, in the county of Cook and State 5 of Illinois, have invented a certain new and useful Improvement in Draft-Rigging for Railway-Cars, of which the following is a full, clear, concise, and exact description, reference being had to the accompanying 10 drawings, forming a part of this specification.

My invention relates to draft rigging for railway cars.

The object of my invention is to provide 15 a draft rigging for railway cars of efficient operation, and one of graduated resisting power.

In the drawings Figure 1 is a plan view partly in horizontal section of a railway 20 draft rigging embodying my invention. Fig. 2 is a side elevation. Figs. 3 to 5 both inclusive are enlarged details, Fig. 3 being a plan view of the compression resisting member and front follower partly in longitudinal section. Fig. 4 is an end view of the front follower. Fig. 5 is a perspective view of the front follower. Figs. 6, 7 and 8 illustrate a modification, Fig. 6 being a plan view partly in longitudinal section of the 25 compression resisting member and front follower, Fig. 7 an end view of the front follower, and Fig. 8 a perspective view of the front follower.

In the drawings 9, 9 represent the draft 30 sills or members of the car frame to which the draft rigging is attached, 10, 10 the front stop members, 11 the rear stop members, 12, the draw bar, 13 the draft yoke, 14 the end sill, 15 the buffer block, 16 the draw 35 bar carry iron—all of well known construction.

17 is a tie and draft yoke carry plate and 40 18 the shell, which is hollow and preferably cylindrical in shape or circular in cross section, open at its forward end and closed at its rear end by the preferably integral transverse rectangular plate 19, which serves as a rear follower. The shell is provided with the internal friction face 20, and contains 45 the springs 21 and 22, which are seated at their rear ends against the rear end of the friction shell.

23, 23 are the segmental friction shoes, 50 preferably three in number, and 24 the 55 wedge.

25 is the front follower comprising a substantially rectangular plate 26 provided on its forward face with the central recess 27 to receive the head of the connecting rod 28. The wall 29 of the recess 27 forms a rearwardly extended boss 30 to engage the wedge 24. Surrounding the boss 30 in the rear face of the plate 26 is the groove 31 in which the forward end of the preliminary spring 32 is seated, the said spring being seated at 60 its rear end against the forward ends 33 of the friction shoes 23. Outside the groove 31 in the rear face of the plate 26 is provided a shoulder 34 with which the forward ends 35 of the friction shell engages upon 65 full compression of the parts within the shell, as illustrated in Fig. 3 of the drawings. The front follower further comprises a rearwardly extended hood 36, which surrounds the forward end of the friction shell 70 75 18 and is in sliding engagement therewith. The boss 30 is sufficiently rearwardly extended to permit a space 37 between the wedge 24 and the said boss of sufficient length to permit the compression of the 80 preliminary spring 32 before the boss 29 engages the wedge 24. Upon the movement of the draw bar and the consequent compression of the gear the preliminary spring 32 is first compressed, and then the boss 29 85 90 engages the wedge 24, bringing into action the friction shoes 22 and the springs 21 and 22.

In the modification illustrated in Figs. 6, 7 and 8 of the drawings the shell 38, the 90 springs 39 and 40, the friction shoes 50, the wedge 51, the connecting rod 52 and the preliminary spring 53 are all identical in construction and operation with the similarly 95 designated parts of the approved forms of construction shown in Figs. 1 to 5 in the drawings. In the modification the front follower 54 consists of a substantial rectangular plate 55 provided on its forward face with the central recess 56 to receive the head of the connecting rod, and provided with the rearwardly extended boss 57 to engage the wedge 51. Surrounding the boss 57 is the groove 58 in which the preliminary 100 spring 53 is seated at its forward end. Said 105 spring 53 engages the friction shoes at its rear end.

I claim:

1. In a friction draft rigging, the combination of the draw bar, draft sills, stop 110

members, draft yoke, friction shell, and a wedge, friction shoes and springs within the shell, with a front follower provided with a rearwardly extending hollow member to receive the front end of the friction shell therein, and a boss within said member engaging the wedge, and a spring seated at its forward end around said boss and at its rear end against said friction shoes.

10 2. In a friction draft rigging, the combination of the draw bar, draft sills, stop members, draft yoke, friction shell, and a wedge, friction shoes and springs within the shell, with a front follower provided upon 15 its rear face with a recess to receive the

friction shell and a boss to compress the wedge within the shell.

3. In a friction draft rigging, the combination of a draw bar, draft members, stop members, a friction shell, friction devices, 20 springs, and a wedge within the shell, with a front follower provided with a rearwardly extending hood in sliding engagement with the shell, and a spring interposed between the front follower and the friction devices. 25

GEORGE A. JOHNSON.
